ADAM TUDOR EYTON, OF NELSON, BRITISH COLUMBIA, CANADA.

MEANS FOR FORMING LEAD WIRE.

1,137,199.

Specification of Letters Patent. Patented Apr. 27, 1915.

Application filed August 4, 1914. Serial No. 354,965.

To all whom it may concern:

Be it known that I, ADAM TUDOR EYTON, a subject of the King of Great Britain, residing at Nelson, in the Province of British Columbia, Canada, have invented certain new and useful Improvements in Means for Forming Lead Wire, of which the following is a specification.

This invention relates to a means for producing a finely divided wire of metallic lead suitable for a certain process for the production of carbonate of lead, the white lead of commerce.

In this process for the production of white lead it is desirable that as large a surface as possible of the metal be exposed to the corroding agents, and these surfaces should be such as will not pack closely in contact with one another. A finely drawn lead wire has been found to be the most effective, and it is to produce this lead wire in a rapid and cheap manner with an inexpensive plant that the device which is the subject of this application, has been devised.

The invention is particularly described in the following specification, reference being made to the drawings by which it is accompanied, in which:

Figure 1 is a longitudinal section through the apparatus complete, and Fig. 2 is a perspective and part section of the lead delivery tumfit or hopper.

In these drawings 2 represents a hemispherical lead melting pot which is suitably supported over a furnace 3, or other means is provided by which the lead may be maintained in a molten state. In the lower part of this melting pot is a delivery aperture 4 which is closable by means of a valve 5 and connected to this aperture 4 is a pipe 6 delivering outside the wall of the furnace into a channel 7 having a removable cover to prevent oxidation. This channel 7 delivers into a tumfit or hopper 9 which is rectangular in plan and in cross section is the frustum of a wedge; and along the bottom of this tumfit is a line of small apertures 10 through which the molten lead pours in a series of small streams. A heating means such as an ordinary Bunsen burner 11^a (see dotted lines, Fig. 2) may be applied at 11 along each side of the bottom of the tumfit to maintain the lead in a fluid condition adjacent to the outflow apertures or any other suitable heating means may be employed. The tumfit 9 is supported over an elongated tank or vessel

12 in which water may be maintained at a substantially constant level about one inch below the outlet apertures 10. Immediately below these outlet apertures an endless traveling band 13 of canvas or the like is movable over a driving pulley 14, which band passes over a pulley 15 at the other end of the tank, and delivers on to an inclined chute 16. The lower end of this band is below the surface of the water and the upper end above the level of the upper edge of the tank. On to this endless band 13 the lead flows from the apertures 10 of the tumfit in a series of small streams which are superficially set as they fall into the water, so that they are substantially circular in cross section; but as they fall on the band the velocity of which is slightly greater than the velocity of the issuing streams the lead is attenuated or drawn out, according to the speed at which the endless band moves, and as a result the lead is delivered to the chute as a finely drawn wire.

The driving pulley of the endless band is preferably below the tumfit as by that means variation in the rate of travel of the band due to its swing or sag is avoided. By this means the wire can not only be produced very cheaply and at a very rapid rate, but so drawn has a loose open surface which is particularly favorable to the corrosive action to which it is subsequently subjected.

Although the specification describes the wire as of circular cross section, and that form has by experience been found to be the most effective for the purpose for which the device has been particularly designed; I do not desire to be confined to such, as a wire or ribbon of any desired cross section and of other material than lead may be produced by the same means.

Having now particularly described my invention, I hereby declare that what I claim as new and desire to be protected in by Letters Patent, is:

1. Means for producing a finely divided wire of lead, said means comprising the combination with a melting pot, of a hopper having a series of small apertures in the bottom into which hopper the molten metal is delivered, an endless traveling band arranged beneath the hopper apertures to receive the metal and a reservoir in which said band projects, a cooling fluid in said reservoir, the cooling fluid emersing said band at the place of said hopper discharge

whereby the molten metal from the hopper passes through the cooling fluid just prior to the delivery of the metal on to the traveling band to cause the metal to be partially 5 surface cooled.

2. Means for producing a finely divided wire of lead, said means comprising the combination with a melting pot having an outflow aperture adjacent to the bottom, and 10 means for regulating the flow of the molten metal therethrough, a duct conveying the molten metal from the outflow aperture of the melting pot to a tumfit having a line of 15 small apertures in the bottom, means adjacent to the outflow apertures of the tumfit for maintaining the metal in a liquid condition, and an endless traveling band beneath the apertures of the tumfit which band is traveling faster than the outflowing metal, 20 and means for imparting a primary surface cooling to the metal as it leaves the tumfit and for rapidly cooling the metal as it is delivered on to the traveling band.

3. Means for producing a finely divided 25 wire of lead, said means comprising the combination with a melting pot having an aper-

ture adjacent to the bottom, and means for regulating the flow of the molten metal through that aperture, of a duct conveying the molten lead to a tumfit having a line of 30 small apertures in the bottom, said tumfit supported over the level of water in a trough and an endless traveling band inclined upward from a position beneath the apertures of the tumfit and below the surface of the 35 water to the level of the upper edge of the tank at the other end.

4. Means for producing a finely divided wire of lead, said means comprising an endless traveling band, means for delivering 40 the molten lead upon said traveling band, means for directing said traveling band faster than the movement of the stream of lead, and means for surface cooling the stream of lead prior to its contact with the 45 traveling band.

In testimony whereof I affix my signature in presence of two witnesses.

ADAM TUDOR EYTON.
